UNITED STATES PATENT OFFICE.

ELMER R. CORWIN, OF CHICAGO, ILLINOIS, ASSIGNOR TO CORWIN TELEPHONE MANUFACTURING COMPANY, A CORPORATION OF ILLINOIS.

TELEPHONY.

1,071,211.

Specification of Letters Patent. Patented Aug. 26, 1913.

Application filed April 24, 1911. Serial No. 622,944.

To all whom it may concern:

Be it known that I, ELMER R. CORWIN, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification:

My invention relates to telephony, and particularly to that class of telephony employing two or more telephone lines; a third telephone line; means whereby either of the first telephone lines may become connected with the third telephone line; means for automatically effecting an extension of the third telephone line, as, for example, would be the case if such third telephone line were a trunk line extending from the stations of the first telephone lines to an automatic or semi-automatic exchange.

My invention in its preferred embodiment includes a number of trunk lines thus extending from an automatic or semi-automatic exchange to the stations of a plurality of telephone lines.

The invention has characteristics which will better be understood by a description of one embodiment of the invention, to which I do not limit myself however, the accompanying drawings illustrating the embodiment of the invention that has been selected for the purpose of disclosing the invention.

Figure 1 of the drawings shows an intercommunicating telephone system illustrated. Fig. 2 illustrates one type of automatically operated selecting mechanism for automatically effecting extensions of the trunk lines at the exchange to which the trunk lines lead, the particular type of equipment shown in Fig. 2 being that with which those skilled in the art are very familiar and which is employed for automatically connecting called subscribers' lines with the lines of calling parties.

In describing the invention illustrated I will omit detailed reference to the means and manner employed by parties at the two intercommunicating stations No. 1 and No. 2 for bringing about telephonic connections between said stations, since all of the apparatus shown below the telephonic equip-

ment at station No. 1 and No. 2 is well known by those skilled in the art.

A trunk line 3 and a trunk line 4 is illustrated as extending from the automatic telephone exchange to each of the stations of the intercommunicating system. There is provided at each of the intercommunicating stations a plurality of selecting keys 11, one individual to each trunk line and each adapted for coöperation with a pin 12 mounted upon a connecting bar 13, whereby each key upon being fully depressed will release its companion so that one key will always occupy a normal position, the lower keys 11 being shown in normal positions. The control that each station has over the trunk line is similar to that possessed by the other and I will therefore describe in detail the association of but one of the intercommunicating stations with the trunk lines with the understanding that such description would apply to each of the other intercommunicating stations, and at this point it should be stated that while my invention has been embodied in connection with an intercommunicating system, I do not limit myself to the use of my invention in connection with intercommunicating stations.

Let it be assumed that station No. 1 desires connection with trunk line 4 and thereafter desires to hold that trunk line so as to establish connection with trunk line 3 or for some other reason. The party at station No. 1, in order to accomplish these objects, will fully depress the selecting key 11 individual to trunk line 4 after having removed his telephone from its switch hook. As a consequence of this operation circuit through the battery 9 at the automatic exchange is closed by way of the sides of the trunk line and a bridge across the sides of the trunk line that is established at station No. 1 and which bridge may be traced from the upper side of the trunk line, the two uppermost contacts of the selecting key 11, the middle armature switch of relay 15 and its alternate contact, the switch hook at station No. 1 and its alternate contact, the telephone receiver and transmitter at this station, the interrupter *a* that is employed when the selected trunk line is to be automatically extended, the right hand armature switch of relay 15 and its alternate contact,

the switch contacts 11¹ of the selecting key 11 to the other side of the trunk line. The manner in which the relay 15 is energized at this stage of the operation is known to those skilled in the practical art and may be described as resulting from a circuit traceable from the upper pole of battery 16, the two uppermost contacts of the switch hook at station No. 1, the resting left hand armature switch of relay 17 and its contact, the winding of relay 15, the engaged contacts 18, to the lower terminal of the battery 16, the contacts 18 being engaged owing to the full depression of the actuated selecting key or switch 11 individual to the trunk line 4. A locking circuit is then established for the relay 15 which may be traced from the upper terminal of the battery 16 through the upper contacts of the switch hook at station No. 1, the left hand armature switch of relay 17, the winding of relay 15, the left hand armature switch of relay 15 and its lowermost contact to the lower pole of the battery 16. As a result, automatic mechanism at the exchange may be operated for extending the trunk lines as a consequence of the circuit interruptions effected by the calling party in manipulating the circuit breaking or dial mechanism *a*.
If the party at station No. 1 should desire to disconnect his telephone from and at the same time hold the trunk line 4 after having secured connection with another party by way of the exchange or after the exchange subscriber has secured connection with station No. 1 by way of the trunk line, then the party at station No. 1 will depress a holding key 22 to bring the normally disassociated relay 23 into association with the trunk line that is to be held, each key 22 at each station being adapted when operated to bring about the association of the relay 23 with the trunk line to which such key is individual and to remove such relay from association with a trunk line with which it was previously associated owing to the mechanical inter-relation between the keys 22 that enables each key to restore each other key 22 to normal position. A releasing key 24 serves to release any key 22 at its station so that the relay 23 will have no operative association. Under the assumption that the trunk line 4 is to be retained by the party at station No. 1, the key 22 individual to the trunk line is placed in the position indicated, whereby a partial circuit is established for the relay 23, this circuit being completed when the button 25 is actuated, each switch 22 being associated with a button or switch 25, there being one such switch 25 for each trunk line. The circuit for the relay 23 that is established by the coöperation of the switches 22 and 25 may be traced from the upper pole of the battery 9, through the upper side of the trunk line 4, the contacts of

the now actuated key 25, the contacts 26 of key 22, the winding of relay 23, the contacts 27 of key 22, the lower side of the trunk line 4, to the lower pole of the battery 9. The relay 23 thereupon establishes a locking circuit through itself and it will be sufficient to trace a bridge connection between the sides of the trunk line through the winding of the relay 23, and which bridge connection is traced from the upper side of the trunk line 4, through the contacts 28, the right hand armature switch of relay 23 and its then engaged contact, the winding of relay 23, the contacts 27, to the lower side of the trunk line. There is thus established a bridge across the trunk line in place of the bridge hitherto traced through the telephone equipment at station No. 1 so that the breaking of the bridge that includes the telephone at station No. 1, and which breaking occurred by the depression of the key 25, is not followed by an operation of the automatic mechanism at the exchange which would disconnect the trunk line from the line automatically connected with it. It is understood that when the key 25 is depressed the telephone equipment at station No. 1 is disconnected from the trunk line 4 because of the consequent release of the button 11, which release is followed by the breaking of the bridge including the telephone at station No. 1 and which breaking occurs at the key 11. The party at station No. 1 is now at liberty to hold conversation with another intercommunicating party, or any other party without the danger of having his conversation transmitted over the trunk line.

When the party at station No. 1 desires to resume connection with the party connected with trunk line 4 he presses the button 11 at his station which is individual to the trunk line 4 so as to reëstablish the telephone bridge between the sides of the trunk line at his station and which telephone bridge was previously traced. This telephone bridge is of low resistance compared with the resistance of the relay 23 so that the relay 23 is de-energized to break the bridge that said relay previously held across the trunk line whereby the apparatus at station No. 1 is again placed in control of the automatic mechanism at the exchange to enable the trunk line to be automatically disconnected at the exchange from its extension when the telephone at station No. 1 is restored upon its switch hook, the only bridge then existing at station No. 1 being broken to occasion this result in a manner well known by those familiar with the art of automatic telephone exchange practice.

I will now more particularly describe the means, which constitutes an important feature of my invention, whereby the relay 23 at each intercommunicating station may be used for the purpose which has been de-

scribed in connection with any of the trunk lines so that it will not be necessary to provide a relay 23 individual to each trunk line at each station. When the relay 23 is un-associated with any trunk line its terminals are free of connection. Each of the terminals of the relay 23 is multiplied, the upper or right hand terminal being multiplied to each of the upper contacts of the contacts 26 while the lower or left hand terminal of said relay is multiplied to each of the upper contacts of the contacts 27. Owing to some previous operation of the key 24, the keys 22 are normal so that these multiplied terminals of the relay 23 are disconnected. It has been described how a depression of the keys 22 and 25 of trunk line 4 will associate the relay 23 with the trunk line 4 and it will be obvious that a similar depression of the key 22 associated with the trunk line 3 will bring about a similar association of the relay 23 with the trunk line 3 when the key 25 individual to the trunk line 3 is operated after the associate key 22 is operated, the key 25 individual to the trunk line 3 having an association with said trunk line similar to the association of the other key 25 individual to the trunk line 4. The circuit which was previously traced as a result of the operation of the keys 22 and 25 individual to trunk line 4 finds its counterpart in the circuit which results from the depression of the keys 22 and 25 individual to trunk line 3.

35 I will now describe the circuits and apparatus by which an appropriated trunk line is rendered busy so that another intercommunicating party seeking connection therewith will know of its busy condition and 40 how the telephone apparatus of an intercommunicating party seeking connection with an appropriated trunk line is prevented from having telephonic connection with such trunk line.

45 Let it be assumed that the party at station No. 2 desires connection with the trunk line 4 at any time after it has been appropriated and whether or not it is held by the apparatus at the intercommunicating station 50 connected therewith. The party at the seeking station, station No. 2, first removes his telephone from its switch hook whereby a circuit is established which may be traced from the upper pole of the battery 16 through the uppermost contacts of the switch hook at station No. 2, the winding of the relay 17, the right hand armature switch of this relay and its normal contact which is a follow up contact, the contacts 29 and 30, 55 the contacts 31 of the now fully depressed key 11 individual to the trunk line 4 at station No. 2, the lower side of the trunk line 4, the contacts 31 of the key 11 at station No. 1 (it now being assumed that telephone station No. 1 is in telephonic connection with

the trunk line 4) the normally positioned contacts 32 at station No. 1, the left hand armature switch of relay 15 and the middle one of its contacts, to the lower side of the battery 16. At this point it will be explained that an alternate circuit connection is established from the contacts 31 at station No. 2 in the event of the key 11 occupying its normal position and of the relay 23 retaining a holding bridge across the trunk line 4 in order that the telephone apparatus at station No. 1 may be disconnected from said trunk line without allowing said trunk line to be appropriated by a seeking station. This alternate circuit is similar to the circuit similarly traced up to and including the contacts 31 at station No. 2, the circuit then continuing from these contacts 31 to the then engaged contacts 33, the two uppermost contacts of the then actuated key 22, the left hand armature switch of relay 23 to the lower pole of the battery 16. With either circuit the right hand armature switch of the relay 17 at station No. 2 makes connection with its alternate contact before it breaks connection with its normal contact, whereby a locking circuit is established for the relay 17 at station No. 2 which may be traced from the upper terminal of the battery 16 through the uppermost contacts of the switch hook at station No. 2, the winding of the relay 17 and its alternate contact to the lower pole of said battery. The magnet 17 after having been energized establishes a busy test circuit which may be traced from the upper pole of the battery 16 through the circuit interrupting apparatus 34, the middle armature switch of relay 17, its then engaged contact, the switch hook at station No. 2, the receiver and transmitter at station No. 2, the dial mechanism *a* at station No. 2, the left hand armature switch of relay 15 at station No. 2 and its normal contact, to the lower pole of the battery 16 by way of the upper side of the intercommunicating telephone line leading to station No. 2. 100

As the relay 15 at station No. 2 has to be energized in order to include the telephone at said station in bridge of the line leading to station No. 2, and as the circuit of this relay depends upon the engagement of the left hand armature switch of relay 17 with its contact, the telephone outfit at station No. 2 is excluded from circuit owing to the fact that the relay 17 at station No. 2 110 was energized as a consequence of the circuit connections resulting from the operation of the key 11 at station No. 2 individual to line 4 and which circuit connections were hitherto traced. Thus the telephone at station No. 2 is locked out of association with an appropriated trunk line in addition to the party at station No. 2 being informed of the busy condition of the trunk line. The trunk lines also test busy and seeking tele- 120

125

130

phones are locked out therefrom when the dial mechanisms *a* are connected with the trunk lines so that the trunk lines cannot be appropriated at those intervals when the 5 circuits through the dial mechanisms are opened. Not only are the telephones locked out of association with trunk lines taken for use but the dial mechanisms of stations seeking connection with trunk lines taken 10 for use are locked out also. In these ways trunk lines are well guarded against the intrusion of stations seeking connection therewith after the trunk lines have been taken for use.

15 In my applications Serial Nos. 622,936 and 622,942 filed April 24, 1911 I have broadly claimed the use of supplemental means for preventing that operation of selecting mechanism that would cause the removal of telephone line extensions which had become connected with telephone lines by the selecting mechanism.

20 While I have herein shown and particularly described one type of equipment carrying out my invention, I do not wish to be limited thereto as changes may readily be made without departing from the spirit of my invention, but

25 Having thus described my invention, I claim as new and desire to secure by Letters Patent the following:

30 1. A telephone exchange system including a plurality of telephone lines; a telephone exchange; a plurality of trunk lines intervening between said telephone exchange and the telephone stations of the aforesaid lines; selecting mechanism at the exchange for automatically connecting extensions with said trunk lines; and means interchangeably associated with the trunk lines for preventing the selecting mechanism from separating a trunk line and the extension connected therewith by the selecting mechanism.

35 2. A telephone exchange system including a plurality of telephone lines; a telephone exchange; a plurality of trunk lines intervening between said telephone exchange and the telephone stations of the aforesaid lines; selecting mechanism at the exchange for automatically connecting extensions with said trunk lines; and electro-magnetic means interchangeably associated with the trunk lines for preventing the selecting mechanism from separating a trunk line and the extension connected therewith by the selecting mechanism.

40 3. A telephone exchange system including a plurality of telephone lines; a telephone exchange; a plurality of trunk lines intervening between said telephone exchange and the telephone stations of the aforesaid lines; selecting mechanism at the exchange for automatically connecting extensions with said 45 trunk lines; means interchangeably associ-

ated with the trunk lines for preventing the selecting mechanism from separating a trunk line and the extension connected therewith by the selecting mechanism; and means for preventing other telephone stations from effecting operative connection with a trunk line with which the aforesaid means has become operatively associated.

4. A telephone exchange system including a plurality of telephone lines; a telephone exchange; a plurality of trunk lines intervening between said telephone exchange and the telephone stations of the aforesaid lines; selecting mechanism at the exchange for automatically connecting extensions with said trunk lines; electro-magnetic means interchangeably associated with the trunk lines for preventing the selecting mechanism from separating a trunk line and the extension connected therewith by the selecting mechanism; and means for preventing other telephone stations from effecting operative connection with a trunk line with which the aforesaid means has become operatively associated.

5. A telephone system including two or more telephone lines each extending from its own station to the station of the other line, there being means governed at the telephone stations whereby telephonic connection may be effected between the stations; a telephone exchange; a plurality of trunk lines intervening between said telephone exchange and the telephone stations of the aforesaid lines; selecting mechanism at the exchange for automatically connecting extensions with said trunk lines; and means interchangeably associated with the trunk lines for preventing the selecting mechanism from separating a trunk line and the extension connected therewith by the selecting mechanism.

6. A telephone system including two or more telephone lines each extending from its own station to the station of the other line, there being means governed at the telephone stations whereby telephonic connection may be effected between the stations; a telephone exchange; a plurality of trunk lines intervening between said telephone exchange and the telephone stations of the aforesaid lines; selecting mechanism at the exchange for automatically connecting extensions with said trunk lines; and electro-magnetic means interchangeably associated with the trunk lines for preventing the selecting mechanism from separating a trunk line and the extension connected therewith by the selecting mechanism.

7. A telephone exchange system including a plurality of telephone lines; a telephone exchange; a trunk line leading to said telephone exchange from the stations of said telephone lines; selecting mechanism at the exchange for automatically connecting ex-

tensions with said trunk lines; means whereby either of the telephone lines may become connected with the trunk lines; means at the stations of said telephone lines for operating 5 the selecting mechanism at the exchange; and apparatus brought into coöperative relation with the trunk line by the stations initially becoming connected therewith for locking out the selecting mechanism operating 10 means of the other station or stations seeking the trunk line.

8. A telephone exchange system including a plurality of telephone lines; a telephone exchange; a trunk line leading to said telephone exchange from the stations of said telephone lines; selecting mechanism at the exchange for automatically connecting extensions with said trunk lines; means whereby either of the telephone lines may become 15 connected with the trunk line; circuit making and breaking means at the stations of said telephone lines for operating the selecting mechanism at the exchange; and apparatus brought into coöperative relation with 20 the trunk line by the stations initially becoming connected therewith for locking out the selecting mechanism operating means of the other station or stations seeking the trunk line.

30 9. A telephone exchange system including a plurality of telephone lines; a telephone exchange; a trunk line leading to said telephone exchange from the stations of said telephone lines; selecting mechanism at the exchange for automatically connecting extensions with said trunk lines; means whereby either of the telephone lines may become connected with the trunk line; means at the stations of said telephone lines for operating 35 the selecting mechanism at the exchange; and apparatus brought into coöperative relation with the trunk line by the station initially becoming connected therewith for locking out other stations seeking connection 40 with the trunk line during the time that the selecting mechanism operating means of the stations first associated with the line is being operated.

45 10. A telephone exchange system including a plurality of telephone lines; a telephone exchange; a trunk line leading to said telephone exchange from the stations of said telephone lines; selecting mechanism at the exchange for automatically connecting extensions with said trunk lines; means whereby either of the telephone lines may become connected with the trunk line; circuit making and breaking means at the stations 50

of said telephone lines for operating the selecting mechanism at the exchange; and apparatus brought into coöperative relation with the trunk line by the station initially becoming connected therewith for locking out other stations seeking connection with the trunk line during the time that the selecting mechanism operating means of the stations first associated with the line is being operated.

55 11. A telephone system including two or more telephone lines each extending from its own station to the station of the other line, there being means governed at the telephone stations whereby telephonic connection may be effected between the stations; a telephone exchange; a plurality of trunk lines intervening between said telephone exchange and the telephone stations of the aforesaid lines; selecting mechanism at the exchange for automatically connecting extensions with said trunk lines; means interchangeably associated with the trunk lines for preventing the selecting mechanism from separating a trunk line and the extension connected therewith by the selecting mechanism; and means for preventing other telephone stations from effecting operative connection with a trunk line with which the aforesaid means has become operatively associated.

60 12. A telephone system including two or more telephone lines each extending from its own station to the station of the other line, there being means governed at the telephone stations whereby telephonic connection may be effected between the stations; a telephone exchange; a plurality of trunk lines intervening between said telephone exchange and the telephone stations of the aforesaid lines; selecting mechanism at the exchange for automatically connecting extensions with said trunk lines; electro-magnetic means interchangeably associated with the trunk lines for preventing the selecting mechanism from separating a trunk line and the extension connected therewith by the selecting mechanism; and means for preventing other telephone stations from effecting operative connection with a trunk line with which the aforesaid means has become operatively associated.

65 In witness whereof, I hereunto subscribe my name this twenty third day of March, A. D. 1911.

ELMER R. CORWIN.
